Design for plate of 'The Lotus' Porcelain Ware, by N. S. Vaudier,
Assigned to Mwarz, Mann, Horwitz & C., of New York, N. Y.
Patented Oct. 1, 1856.

Fig. 842.

Dec. 842

N. S. Neder, of Troy, N.Y.
Assignor to
Mann, Torrance, & Co., of Troy, N.Y.
Letters Patent No. 842, Dated October 7, 1856.

The Schedule referred to in these Letters Patent and making part of the same.

To all whom it may concern.

Be it known that I, N. S. Neder, of the City of Troy, in the County of Rensselaer, and State of New York, have invented or produced a new and original design, which I call "The Lotus" for plates of cooking stoves; and I do hereby declare that the following is a full and exact description of the same, reference being had to the annexed drawings making a part of this specification, in which:

Figure 1, is an elevation of a large oven door.

Figure 2, a section at y.z, and:

Figure 3, at w.x, of the same, and:

Figure 4, is an elevation of a small panel ~~at a door, side or end plate.~~

Figure 5, a section at u.v, and:

Figure 6, at s.t, of the same.

The same letters refer to like parts in all the figures.

My design for the panels of the large doors consists of the compound border moulding A, having a lobed leaf B, at each angle, and the large oval swelling ornament

2

Des. 842

which is composed of the central knot or scroll C, the coils of notched rays D, and the intermediate fluted rays E. My design for the small panels resembles that for the large, consisting of the compound border moulding F, with a leaf G, in each corner, and the large, oval, swelling ornament, which is composed of the raised scroll H, at the center, the notched rays I, arranged at right angles with each other, and the intervening fluted rays J.

What I claim as my invention or production, and desire to secure by Letters Patent, is the ornamental design herein described and represented in the annexed drawings, for panels of plates of cooking stoves.

Witnesses.
